(57) **CLAIM**

The ornamental design for a camera mount, as shown and described.

DESCRIPTION

FIG. 1 is a first perspective view of a camera mount showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 1.

The broken lines shown in the drawings depict portions of the camera mount that form no part of the claimed design. The dashed lines shown in the drawings depict portions of the camera mount that form no part of the claimed design. The dot dash lines represent a boundary for the purposes of disclosing areas of enlargement and form no part of the claimed design.

1 Claim, 9 Drawing Sheets
